UNITED STATES PATENT OFFICE.

MAX J. MILZ, OF TAFT, CALIFORNIA.

PUMP-GEAR CABLE GUIDE.

Application filed July 8, 1921. Serial No. 483,269.

To all whom it may concern:

Be it known that I, MAX J. MILZ, a citizen of Austria, residing at Taft, in the county of Kern, State of California, have 5 invented certain new and useful Improvements in Pump-Gear Cable Guides; and I do hereby declare the following to be a full, clear, and exact description of the invention, such as will enable others skilled in 10 the art to which it appertains to make and use the same.

This invention relates to new and useful improvements in cable guides and particularly to cable guides used in connection 15 with oil or water pumping plants.

One object of the invention is to provide a device which will properly guide and support the power cable so that the cable will be permitted to perform its work without 20 injury thereto.

Another object is to provide a support for the cable which has adjustable means for regulating the tension of the cable.

Another object is to provide a novel and 25 improved mounting for the swinging arm which supports the cable.

Other objects and advantages will be apparent from the following description when taken in connection with the accompanying 30 drawing.

In the drawing:

Figure 1 is an elevation of the device. Figure 2 is a top plan view of the same.

Figure 3 is a vertical longitudinal central sectional view on the line 3-3 of Figure 2.

Referring particularly to the accompanying drawing, 10 represents a metal plate which is properly secured on a cement foundation 11, and has extending vertically from 40 its upper face a stem 12 the upper end of which is greatly reduced in diameter to form the stud 13. Rotatably supported on the stem 12 is a collar 14, and formed integrally with the collar, and extending horizontally from one side thereof is a socket member 15, the bore 16 of which widens inwardly toward the collar, as clearly seen in the sectional view Figure 3. Held in the 45 socket member 15, by means of the Babbitt-metal 15', and extending horizontally outward therefrom, is an arm 17, and on the outer end of the arm is secured the longitudinally bifurcated member 18. The inner end of the member 18 is formed with a

socket 19, similar to the socket 15, the outer end of the arm 17 being held therein, by the Babbitt-metal 19', in the same manner as the other end of said arm is held within the socket 15. In the upper and lower portions of the bifurcation of the member 18 are formed the longitudinal series of openings 20. Disposed within the bifurcation is a metal plate 21, the inner or rear face of which is formed with an eye 22 arranged to register with corresponding openings in the upper and lower portions of the bifurcation to receive the bolt 23. Secured to the outer face of the plate by means of the lag screws 21', and extending longitudinally thereof, is a wooden block 24, the outer lower edge face of which is formed with a longitudinal groove 25 in which is received the cable 26.

As will be clear from an inspection of 75 the drawing, the plate 21 is adapted to rock, while the arm 17, and the attachments at its ends will swing horizontally, upon reciprocating movement of the cable. This prevents chafing of the cable, and greatly 80 lengthens the life thereof.

To change the tension of the cable, the bolt 23 is removed and the plate 21 secured by said bolt in another pair of openings of the bifurcation.

Engaged on the stud 13, and secured in position thereon, to maintain the collar in proper position, is a cup 27, the bottom wall of which is formed with an opening 28 to permit the escape of oil from the cup to 90 the stem and collar, for the purpose of lubrication.

While I have shown the arm 17 as extending at right angles from the member 14, it will be understood that the same may 95 extend at different angles thereto, in accordance with the position of the cable being operated upon.

What is claimed is:

1. A cable support and guide for a well 100 pumping system comprising a base having a stem, a collar rotatably supported on the stem and having an arm extending therefrom, the outer end of the arm being bifurcated, a plate pivotally supported in the 105 outer end of the bifurcation, and a grooved cable receiving block secured to said plate.

2. A cable support and guide for a well 110 pumping system comprising a support, a collar rotatably supported on the support, a bi-

furcated arm carried by and movable with the collar, and a removable cable receiving block mounted in the outer end of the arm.

3. A cable support and guide for a well pumping system comprising a support, a collar rotatably mounted on the support, a bifurcated arm carried by and movable with the collar, a member pivotally mounted in the outer end of the bifurcation of the arm,

and a removable block mounted on the 10 pivoted member and having a longitudinally curved groove for the reception of a cable.

In testimony whereof, I affix my signature, in the presence of two witnesses.

MAX J. MILZ.
